UNITED STATES PATENT OFFICE.

JAMES A. MOULD, OF MILWAUKEE, WISCONSIN, ASSIGNOR TO EVINRUDE MOTOR COMPANY, OF MILWAUKEE, WISCONSIN.

OUTBOARD MOTOR.

Application filed March 5, 1923. Serial No. 622,740.

To all whom it may concern:

Be it known that I, JAMES A. MOULD, a citizen of the United States, residing at Milwaukee, county of Milwaukee, and State of Wisconsin, have invented new and useful Improvements in Outboard Motors, of which the following is a specification.

This invention relates to improvements in outboard motors, and more particularly to steering and reversing mechanism therefor.

The general type of steering mechanism to which this invention relates is disclosed in Patent No. 1,191,211, issued to C. J. Meyer, July 18, 1916. It is applicable to a type of motor in which an upright drive shaft is enclosed within a tubular housing which supports a submerged gear housing, wherein a propeller shaft is journaled. A tiller is connected with the tubular shaft housing through a latch mechanism such that the tiller may be used to oscillate the housing through the latch mechanism to direct the propeller from side to side for steering purposes. When a reversal of the direction of propeller thrust is desired, the latch mechanism is released and the dirigible tubular shaft housing is allowed to make a turn of 180° and is re-engaged by the latch for steering purposes.

In mechanisms which have frequently been constructed along the lines suggested above, the torque of the driving gear, continuously exerted through the dirigible shaft housing during engine operation, has been relied upon to maintain said housing against movement in one direction with respect to the latch. In the other direction the latch has provided a positive stop. When the motor has ceased to operate, however, the torque referred to above has been inoperative, and as a result, little or no steering of the craft has been possible subsequent to the stoppage of the engine. Under such conditions a rudder blade movable with the dirigible housing and propeller would be of no avail, since as long as the engine is in operation, the propeller is dirigible and its thrust is used for steering, and when the engine is at rest there is no operable connection between the tiller and the dirigible submerged parts.

The present invention contemplates the provision of a rudder blade upon the dirigible housing which carries the propeller

shaft. In order to make the rudder available for steering when the engine and propeller are at rest, it is further contemplated to provide a positively acting latch for releasably engaging the dirigible shaft housing with the tiller and locking these parts against relative rotation in either direction.

Broadly stated, it is the primary object of this invention to provide in an outboard motor of the type described a positively acting releasable latch mechanism adapted normally to connect the tiller to the dirigible submerged parts of the motor in such a way that steering is possible, as long as steerage way exists, even though the engine is at rest.

It is a further important object of this invention to provide for an outboard motor a bracket mounting so designed as to permit the submerged parts of the motor to swing upwardly about the bracket when a submerged obstruction is encountered, and to provide in such a construction a novel tiller which will be rigidly connected with the motor for steering purposes but will be hinged upon a transverse horizontal axis so that it may substantially retain its normal position during the tilting of the motor as aforesaid. Incidentally to the above stated object, it is also an object of this invention to provide in a tiller hingedly connected with an outboard motor, a latch controlling mechanism, operable in any position of the tiller to effect the release of the latch by which the reversal of the propeller and rudder is controlled.

In the drawings:

Figure 1 is a sectional view taken on line 1—1 of Figure 2 and illustrating the internal construction of tiller and latch mechanism embodying this invention.

Figure 2 is a side elevation of an outboard motor embodying this invention.

Figure 3 is a sectional view similar to that illustrated in Figure 1, and illustrating a modified construction of latch and tiller mechanism.

Figure 4 is a section taken on line 4—4 of Figure 1.

Figure 5 is a section taken on line 5—5 of Figure 2.

Figure 6 is a section taken on line 6—6 of Figure 2.

Figure 7 is a section taken on line 7—7 of Figure 6.

Like parts are identified by the same reference characters throughout the several views.

The outboard motor which is shown complete in Figure 2 may be of the general type disclosed in the patent to Evinrude, No. 1,001,260, August 22, 1911. The device includes a crank case 10, cylinders 11, and fly wheel 12. The fly wheel is mounted upon a crank shaft 9 which leads downwardly, as disclosed in said patent, through a dirigible shaft housing 13 to a submersible gear housing 14, wherein suitable gearing connects the crank shaft with a propeller shaft 15 upon which the propeller 15 is mounted. Constructional details which are fully shown in the Evinrude patent named above, and which are unnecessary to an understanding of the present invention, have been omitted from the drawings herein in order to simplify the disclosure.

The bracket 16 is adapted to support the entire motor including the internal combustion engine, driving connections, and propulsion mechanism from the stern or transom of a row boat or other small craft. The bracket is provided with spaced arms 17 and 18, the latter of which is elongated to extend downwardly outside of the transom 30 to a point adjacent the water line. A set screw 19 in the shorter arm 17 of the bracket may be turned up to engage the transom of a boat with a clamping pressure.

Immediately beneath crank case 10 is a casing 22 which houses latch mechanism forming an important part of this invention and hereinafter to be described in detail. The casing 22 is preferably secured by bolts to the crank case 10, or is otherwise made fast thereto. A sleeve 23 extends downwardly from the latch casing 22 and is revolvable within a two-part bearing sleeve 24 which is clamped thereon by bolts 25 passed through registering apertures in flanges 26. One of the parts of this clamping sleeve carries a rearwardly projecting ear 28 which lies between similarly formed ears 29 and 30 of bracket 16. Each of the ears aforesaid is apertured and a pintle 31 extends through them all, thereby providing a hinged joint between the bracket 16 and the two-part bearing sleeve 24. The peripheral flange 33 of the bearing sleeve is in supporting relation to the shoulder 34 of the sleeve 23 which is integral with the latch casing 22. Thus, the bearing between shoulder 34 and the peripheral flange 33 of the two-part bearing sleeve 24 carries the entire weight of the engine and propulsion mechanism. Upon this bearing the engine and propulsion mechanism may be oscillated as a unit upon the axis of bearing sleeve 24 for steering purposes. The dirigible tubular housing 13 for the downwardly extended crank shaft 9 is rigidly connected with the

submersible gear housing 14 in which the propeller shaft is journaled. Thus, when the engine and related parts are oscillated in bearing sleeve 24, the direction of the thrust of propeller 15 is angularly adjusted and effects the steering of the craft to which the motor is attached. Steering is further facilitated by the webs or fins 35 which are preferably integral with the submersible gear housing 14 and comprise a rudder dirigible 75 with said housing.

The latch mechanism releasably connecting the tiller with the dirigible tubular housing 13, and the attached submersible gear housing 14 and rudder 35 will now be 80 described.

The dirigible tubular housing 13 extends upwardly through the sleeve 23 which forms an integral part of the latch casing 22. The annulus 36 disposed within the latch casing 22 provides a tubular portion 27 which extends downwardly into the dirigible shaft housing 13 and is sweated or otherwise secured thereto. This annulus carries upon its periphery a pair of symmetrically disposed radially projecting lugs 29 with which dogs are engageable to effect the latching operation.

In the construction shown in Figures 1, 4, and 5, the dogs 40 and 41, pivoted respectively to latch casing 22 upon pins 42 and 43, are used. The direction of rotation of crank shaft 9 is indicated by an arrow in Figure 1, and this arrow also indicates the direction of application of torque to the dirigible shaft housing 13 and to the annulus 36 during such periods as the internal combustion engine which drives the crank shaft 9 is operative. This torque is opposed therefore by the dog 40, the shoulder 44 of which may be engaged with either of the lugs 39 to oppose the rotation of annulus 36 or the shaft housing and related parts. In the position in which they are shown in the drawings, the thrust of the propeller is exerted rearwardly and the motor is said to be in reverse. If, however, the dog 40 be actuated through mechanism hereinafter to be described, to its releasing position, the dirigible tube 13 will be allowed independently to rotate 180° before the opposite lug 39 will contact with shoulder 44 of dog 40.

The dog 41 is provided with a cam face 45 and is shouldered at 46 to seat against one of the lugs 39 opposite to that with which dog 40 is engaged. A spring 47 is compressed in a suitable pocket 48 in the latch casing 22 and serves to maintain dog 41 normally pressed into operative relation to the lugs with which it is engageable. When the dirigible shaft housing 13 and annulus 36 are released by latch 40, however, and are in rotation independently of the latch casing 22, each lug will, as it rotates, act upon the cam surface 45 of dog 41 to

push said dog outwardly against the compression of spring 47 sufficiently to permit the lugs to pass shoulder 46. Dog 41 acts automatically, therefore, as a pawl to engage either lug and to prevent any relative rotation between the annulus 36 and casing 22 in a direction opposite to that indicated by the arrow.

Projecting laterally from the latch casing 22 is a bearing 50 upon the exterior of which is journaled the sleeve 51 of an elbow member 52. The sleeve 53 of the elbow is offset vertically above the sleeve 51 thereof and extends at right angles to sleeve 51. The elbow member 52 is held in place upon bearing 50 by means of a bolt 54 which extends transversely through the latch casing 22 and through the bearing member 50 to the exterior of elbow 52. Pawl 40 is forked at its free end 55 to receive the bolt 54. A spring 56, centered upon and guided by the bolt, seats against the forked end 55 of pawl 40 and maintains said pawl 40 normally in operative engagement with one of the lugs 39 upon the annulus 36. A sleeve 57, slideable within the bearing 50 and upon bolt 54, serves as a plunger to actuate pawl 40 to releasing position against the compression of spring 56.

The tiller includes a tubular rod 60 which is secured within the arm 53 of elbow 52. The hand grip 61 is rotatable upon rod 60 and is connected through a cylindrical block 62 with a shaft 63 that extends axially of the tiller. This shaft may conveniently be provided with a bearing 64 adjacent the rear end of the tiller rod 60. The extremity of the shaft 63 carries a lever 65 within the offset portion of elbow 52. The free end of the lever is forked as shown at 66 in Figure 4 and straddles the bolt 54 for engagement with the slideable sleeve 57. The arrangement is such that when the hand grip 61 is rotated counter-clockwise, as viewed in Figure 1, shaft 63 and lever 65 will be oscillated upon the axis of said shaft and will thereby force the slideable sleeve 57 and the forked end 55 of pawl 40 against the compression of spring 56. The pawl is thereby moved to releasing position and the lug 39 will be released to permit the dirigible housing 13 and attached parts to rotate continuously in the direction indicated by the arrow in Figure 1 so long as the grip remains in a position such as to retract pawl 40. If, however, the hand grip is released immediately following its initial counter-clockwise movement, the compression of spring 56 will cause pawl 40 and the actuating mechanism therefor to move toward a normal position, and said pawl will serve as a stop to engage the next lug 39 which is presented to shoulder 44 in the course of the rotation of annulus 36, dirigible housing 13, and attached parts.

It will be noted that the mounting of the tiller upon elbow 52, which is rotatably supported from the bearing 50 of latch casing 22, is such as to permit the tiller to move freely in a vertical plane about the transverse axis of said bearing. Since the center of oscillation about which the tiller is movable coincides with the axis of the slide sleeve 57, it will be obvious that an operative relation will always exist between lever 65 and said sleeve, irrespective of the particular position of adjustment in which the tiller may be maintained at the time. It will further be noticed that no tiller movement in a horizontal plane is possible without a corresponding movement of the latch casing 22. Inasmuch as the latch casing is rigidly connected with the entire engine and is connected through pawls 40 and 41 with the dirigible shaft housing 13, submerged gear casing 14 and related parts, it follows that when the tiller is oscillated from side to side in a horizontal plane, the entire engine and propulsion mechanism of the motor must oscillate within the two-part bearing sleeve 24 which has already been described. If, however, the grip 61 be momentarily rotated upon its axis to cause dog 40 to release the lug 39 with which it is engaged, the dirigible shaft housing 13, together with submerged gear casing 14 and related parts, will rotate independently of the engine and tiller for 180° until a second lug 39 comes in contact with the normally positioned dog 40. In this manner the reversal of the motor is accomplished, the reversal of the thrust of the propeller being brought about by a bodily movement of the propeller to a diametrically opposite position with reference to the housing 13 by means of which the propeller is supported. In Figure 2 the propeller is indicated in full lines in a position such that it will propel rearwardly a craft to which this outboard motor is attached. In dotted lines the propeller is shown in its forward-driving position.

As has previously been explained and as can be readily understood, the torque of the crank shaft 9 transmitted through the bevel gearing in the submerged gear housing 14 to the propeller shaft, tends to maintain the propeller shaft and submerged gear housing in rotation upon the axis of the crank shaft. Since the submerged gear housing 14 and the dirigible shaft housing 13 are rigidly connected, this torque is also transmitted to the shaft housing 13 tending to turn it in the same direction in which the shaft rotates, to wit, in the direction indicated by the arrow in Figure 1. This torque is continuous during engine operation and tends at all times to maintain one of the lugs 39 in contact with the positive stop provided by the shoulder 44 of dog 40.

When the engine is at rest, however, it will readily be appreciated that no force will exist tending to maintain either of the lugs 39 in contact with dog 40 so that if the tiller 5 were moved to the right, as viewed in Figure 1, it would, except for the provision of pawl 41, leave the annulus 36, shaft housing 13, and the rudder motionless and unmoved by the tiller. Pawl 41 ensures that when one 10 of the lugs 39 has once contacted with shoulder 44 it will stay there. Thereafter, shoulder 44 transmits tiller movements in one direction to the rudder and shoulder 46 transmits tiller movements in the opposite direction 15 to the rudder. A positive latch is thereby provided for connecting the tiller with the rudder, even though the engine be at rest. Equivalent results may be secured in many different ways. The modified construction 20 illustrated in Figure 3 may be used to replace the construction shown in Figures 1, 4, and 5, if desired.

The annulus 36 in the modified construction may correspond exactly to that shown 25 in the other figure. As illustrated, it is slightly modified, but the change in form is regarded as immaterial.

The latch casing 22 is altered to provide 30 a recess 68 in which the screw-threaded member 69 is rotatable. The bearing 50' corresponds in general to bearing 50 but is disposed at right angles to the position of bearing 50, and therefore extends directly 35 forwardly in the normal position of the dirigible parts. The shaft 63' which extends through bearing member 50' has the screw-threaded member 69 keyed to it for rotative movement therewith. A set screw 70 threaded 40 in the latch casing 22 bears against the end of shaft 63' and permits wear to be taken up so that no axial movement of the screw-threaded member 69 will be possible.

The bearing member 50' carries a pair of 45 offset and forwardly projecting ears 72 between which are disposed the forwardly projecting ears 73 of bearing member 74. Each of the ears 72 of bearing member 50' is connected to one of the ears 73 of the bearing member 74 by pivot pins 75, the two pivot pins being in transverse axial alignment. The shaft 63' is universally jointed at 76 upon the axis of pivot pins 75, and an outer section of the universally jointed shaft finds 50 a bearing in bearing member 74. The grip 61' is made fast to the outer end of shaft 63', so that a rotative movement of the grip will be transmitted directly to the threaded member 69 on the inner end of said shaft.

It will be noted that the grip and the 60 outer end of shaft 63' can not be moved in a horizontal plane, either to right or left, without correspondingly actuating the latch casing 22. The grip, however, and the outer end of the shaft 63' are free to be moved in a vertical plane about the axis of pins 75, and

at any point of movement in said vertical plane the universal joint at 76 will permit the rotative movement of the grip to be transmitted to the threaded member 69. Thus, steering may be effected through the 70 grip whether the grip be held in a lowered or in an elevated position, and likewise, reversing may be effected by the rotation of the grip whether the grip be held in an elevated or in a lowered position. 75

The screw-threaded member 69 will be noted to be provided with a pair of helical threads 77 which are spaced apart sufficiently to receive between them either of the lugs 39 upon annulus 36. These threads 80

terminate flush with the rearwardly disposed plane surface 78 of the member 69 upon which the threads are formed. This plane surface obviously is adapted to serve as a positive stop against which the lugs 39 may contact, subsequent to their independent rotation during the reversal operation. When a lug has so contacted, the operator can turn the grip 61' sufficiently to feed a lug 39 into the valley between the two threads 77 where 85 it will be engaged upon each side by one of said threads. A lug 39 is shown to be so engaged in Figure 3. Obviously, when so engaged, the lugs serve to lock the annulus 36 positively to the latch casing 22, so that regardless of the direction in which the tiller grip 61' is moved, with respect to annulus 36 and the dirigible parts of the propulsion mechanism, there must always be a positive connection between the tiller and such dirigible parts. 90

When a reversal of the dirigible parts of the propulsion mechanism is desired, the tiller grip 61' is merely given an added rotation in a clockwise direction, whereby the

lug 39 will be fed completely through the threads 77 and will be delivered at the forward side of such threads. 105

Thereafter it will be free to move in the direction indicated by the arrow and the torque existing 110 as aforesaid upon the dirigible shaft housing 13 will serve to carry the annulus 36, shaft housing 13, and all the submerged parts of the motor through a rotation of 180°, or approximately that angle, until the opposite lug 39 contacts with the face 78 of threaded member 69 and is thereby brought to rest. It will be noted that whereas the device shown in Figures 1, 4, and 5 requires for its operation that the operator shall release the grip and permit spring 56 to move the parts to their original positions, the device shown in Figure 3 is such that the grip 61' is always rotated for a partial revolution in a clockwise direction whether it be desired to release one of the lugs 39 or to engage a lug which has just been stopped by face 78 as aforesaid. 115

It has already been intimated herein that 120 the purpose of providing the pivotal connec-

tion of the engine propulsion mechanism upon the transverse pintle 31 of bracket 16 is to permit the entire mechanism so mounted to swing about said pintle when the submerged parts of the device encounter an obstacle in the water. Where such a pivotal movement of the operating parts of the outboard motor is to take place, and where the motor is reversible as in the present case, it is obviously necessary to provide some type of mechanism capable of connecting the submerged parts rigidly to bracket 16 during the periods of reversal in order that the thrust of the propeller may not draw it upwardly about the pintle 31 and out of the water. At such times as the motor is not in reverse, the thrust of the propeller will, of course, maintain the submerged parts in contact with the bracket unless an obstruction is encountered, at which times the obstruction will overcome propeller thrust and will throw the propulsion mechanism upwardly out of the way.

In achieving this construction, wherein the propulsion mechanism is rigidly connected with the bracket during reversal and is released when the motor is operating to drive the craft forwardly, a latch mechanism has been worked out which is disclosed more particularly in a co-pending companion application. The mechanism will, however, be briefly described herein in order that the operation of this outboard motor may be completely understood.

The downwardly extending bracket 18 carries adjacent its lower extremity rearwardly projecting members 80 which are spaced apart and provided at intervals with apertures adapted to receive said screws, whereby a block 81 is adjustable forwardly and rearwardly between said members. The members 80 are preferably arcuate and concentric with pintle 31 about which the operating parts of the outboard motor are pivotally movable.

Block 81 is provided with a cylindrical bore 82 which extends through it from top to bottom. There is also a port at the rear of the block which is cut through the block from top to bottom and enables any member of the diameter of dirigible shaft housing 13 to pass freely into and out of the cylindrical bore 82. The walls of the port, however, are laterally notched, the notches being disposed in staggered relation. There will preferably be at least three such notches. In the embodiment of the invention which is shown in the accompanying drawings, an upper notch 83 and a lower notch 84 extend to the left, whereas an intermediate notch 85 extends to the right. Excluding such notches from consideration, the rearwardly opening port in block 81 is of barely sufficient size to receive tubular shaft housing 13.

Mounted upon the tubular shaft housing at a height registering with the notches 83, 84, and 85, respectively, are a series of arcuate lugs 86, 87, and 88. These lugs are of the form clearly shown in Figure 7, 70 wherein the upper lug 86 appears completely in plan. It will be noted that the lugs project alternately upon opposite sides of the dirigible shaft housing 13 so that when one of said lugs is brought, by the rotation of 75 the shaft housing, into registry with one of the notches in the walls of the port rearwardly opening through block 81, each of the other lugs will also be in registry with its corresponding notch. When the lugs are 80 in registry with one of the laterally extending notches of said port, it will obviously be possible not only to move the dirigible shaft housing 13 through said port but also to move with it the arcuate lugs which it carries. When, on the other hand, the dirigible shaft housing is rotated more than a few degrees in either direction, the result will be 85 to move the arcuate lugs toward the position in which they appear in Figures 6 and 7 of 90 the drawings, wherein it will be clear that they fail to register with the notches to which they are opposite. Obviously, in this position the dirigible shaft housing 13 and all of the propulsion mechanism will be 95 locked to the bracket and incapable of moving about pintle 31.

The arrangement is such that the locking interaction between the lugs on the dirigible shaft housing 13 to the walls of the cylindrical bore 82 in lock 81 will only occur when the motor is in reverse. In other words, when the latch mechanism in latch casing 22 is released in the manner already described, by a partial rotation of the tiller grip, and when as a consequence of such release the dirigible shaft housing and all of the propulsion mechanism carried thereby is permitted to rotate through 180° for the purpose of effecting a reversal of the motor, the lugs 86, 87, and 88 will be brought by the rotation of shaft housing 13 to a position where they cannot register with notches 83, 85, and 84 respectively. Thereupon, the rearwardly directed thrust of the propeller, which is in the position shown in Figure 2, will be communicated through the shaft housing 13 to the lugs thereon to block 81 and thence through spaced members 80 to the bracket. When, however, the latch mechanism in latch casing 22 is again released by partial rotation of the tiller, the propeller and dirigible shaft housing will assume the position indicated in dotted lines in Figure 2, and, by the partial rotation of the shaft housing the lugs thereon will be brought into complete registry with the notches in block 81, and thereafter the shaft housing will be maintained within said block only by the thrust of the propeller. The entire mecha- 110
100
105
115
120
125
130

nism will be free to oscillate about pintle 31 should an obstruction be encountered.

It will be noted that the lugs 86, 87, and 88 are not cut upon a chord of the circle in which their margins lie. The particular form in which they appear has been adopted in order that the shaft housing 13 may be swung or oscillated slightly upon its axis during steering without moving the lugs to a point such that they might become locked within block 81. In this particular embodiment of the invention the curve of the lugs is such that an angular movement of the tiller through 35° upon either side of its center line is possible without effecting the interlocking of the dirigible shaft housing with block 81.

When the engine and submersible parts swing upwardly as in encountering a submerged obstacle, it will be obvious that if the tiller were rigidly connected with these dirigible parts it would be forced to travel through a corresponding arc in a vertical plane and might bring the hand of the operator into forcible and undesirable contact with the rear side of the craft to which the outboard motor is attached. To avoid such a possibility, the free vertical movement of the tiller, with respect to the latch casing 22 which has already been described, is provided. It will be remembered that in both of the alternative constructions which are disclosed in Figures 1, 3, 4, and 5, means is provided whereby the grip can move freely in a vertical plane while retaining an operative connection with the remainder of the device, both for steering purposes and for reversal. It is impossible, therefore, for the engine and propulsion mechanism, in oscillating about the pintle 31 by which it is connected to the bracket, to affect in any way the position of the tiller which will at times be independently within the control of the operator's hand and will take this position from the position of said hand.

I claim:

1. In a device of the character described, the combination with a dirigible part and a shaft housing independently rotatable concentrically with said part for reversing purposes, of a manually releasable dog engageable with said shaft housing to secure it against rotation in one direction with respect to said part and an automatically engageable dog opposed to said manually releasable dog and adapted to secure said shaft housing against rotation in the other direction with respect to said part.

2. In a device of the character described, the combination with a dirigible part and a tiller connected therewith and having a portion mounted for independent movement, of a shaft housing independently rotatable concentrically with said part and provided with

an outstanding lug, a dog pivotally mounted on said part and operatively connected with the independently movable portion of said tiller whereby said dog may be oscillated by said tiller portion, a spring normally maintaining said dog in the path of said lug whereby to prevent relative rotation of said shaft housing in one direction with respect to said part, said dog being releasable by said tiller portion to permit of rotation in said direction and a second oscillatory dog automatically adjustably spring pressed into the path of said lug and adapted in one position of said lug to secure said lug against rotation in a direction opposite to that aforesaid, said firstmentioned dog and last last-mentioned dog being adapted for co-operation to lock said housing against rotation in either direction relative to said part.

3. In an outboard motor having dirigible and reversible submersible parts, the combination with a rotatable member connected with said parts, of a tiller pivotally mounted for oscillation in a substantially vertical plane, about an axis transverse with respect to the longitudinal extent of said tiller, latch mechanism reversibly connecting said tiller with said rotatable member, means carried by said tiller for releasing said latch mechanism, and motion transmitting connections between said means and said latch mechanism and arranged to be unaffected by the oscillation of the tiller about said axis.

4. In an outboard motor having dirigible and reversible submersible parts, the combination with such parts, of a member connected for movement therewith, oppositely projecting lugs upon said member, a spring pressed dog normally disposed in the path of movement of said lugs, a substantially horizontal dog actuating member, whereby said dog is movable to a lug releasing position, a tiller adjustable about an axis including said dog actuating member, a lever fulcrummed upon an axis offset from the axis upon which said tiller is adjustable, a portion of said lever being in motion transmitting relation to said dog actuating member, and means carried by said tiller for oscillating said lever upon its fulcrum, whereby said dog may be actuated to lug releasing position irrespective of the position of adjustment of said tiller.

5. In an outboard motor the combination with a bracket, of a frame member supported therefrom for oscillation about an upright axis, a housing member extending downwardly from said frame member and movable independently thereof, propulsion and steering devices supported from said housing member and connected thereto for movement therewith, a tiller member hingedly connected with said frame member for independent oscillation in a vertical plane and positively connected with said

frame member for simultaneous oscillation therewith about the axis of said frame member, latch mechanism for releasably engaging said frame member with said housing, 5 and means associated with said tiller member for effecting a release of said latch mechanism.

6. An outboard motor including the combination with a bracket, a bearing member 10 pivoted thereto upon a transverse axis, a frame member supported from the bearing member and rotatable thereon on an axis substantially at right angles to said first mentioned axis, a housing rotatable independently of said frame member upon an axis parallel to the axis thereof, propulsion mechanism supported from said housing and dirigible therewith, a tiller hingedly connected with said frame member for independent movement about a transverse axis, latch mechanism for releasably engaging said member with said housing, and manually operable means associated with said tiller for effecting the release of said latch 20 mechanism, said means being operable in any position of adjustment of said tiller about its transverse axis.

7. In an outboard motor including the combination of a bracket, of a frame member supported from said bracket and oscillatable about a transverse horizontal axis and a normally upright axis substantially at right angles to said transverse axis, a housing rotatably adjustable independently 30 of said frame member upon the normally upright axis thereof, propulsion mechanism supported from said housing, an engine supported from said frame member and adapted to oscillate therewith upon the normally upright axis thereof, motion transmitting connections extending through said housing between said engine and said propulsion mechanism, a tiller connected with said frame member for the oscillation thereof upon its 40 normally upright axis, and latch mechanism releasably connecting said frame member with said housing against relative movement in either direction.

8. In an outboard motor including the combination with a bracket, of a frame member supported from said bracket and oscillatable about a transverse horizontal axis and a normally upright axis substantially at right angles to said transverse axis, a housing rotatably adjustable independently of said frame member upon the normally upright axis thereof, propulsion mechanism supported from said housing, an engine supported from said frame member and adapted 50 to oscillate therewith upon the normally upright axis thereof, motion transmitting connections extending through said housing between said engine and said propulsion mechanism, a tiller connected with said frame member for the oscillation thereof upon its 55

normally upright axis, and latch mechanism releasably connecting said frame member with said housing, said tiller including a grip portion adjustable in a vertical plane independently of said frame member together with means operably connecting said grip portion with said latch mechanism for the manual release thereof.

9. An outboard motor including the combination with a bracket, of a frame member supported from said bracket and mounted for oscillation upon a transverse and substantially horizontal axis and upon a normally upright axis substantially at right angles to said transverse axis, an internal combustion engine cylinder supported from said frame member and movable therewith, a housing extending downwardly from said frame member and independently rotatable with respect thereto, propulsion mechanism supported from said housing and dirigible therewith, a drive shaft extending through said housing to said propulsion mechanism and provided with a crank in registry with said cylinder, interlocking mechanism carried by said housing and by said bracket and arranged for engagement in one range of positions of rotation of said housing and for release in a second range of positions of said housing, a tiller having a grip portion hingedly adjustable upon a transverse axis and connected with said frame member for oscillation therewith upon the normally upright axis thereof, latch mechanism within 90 said frame member adapted to releasably engage the frame member with said housing, and latch actuating mechanism extending operatively along said tiller to the grip portion thereof.

10. An outboard motor including a frame member mounted for oscillation upon a normally upright axis, a housing member extending downwardly from said frame member and independently rotatable with respect thereto, propulsion and steering devices supported from said housing and dirigible therewith, a tiller connected with said frame member for effecting the oscillation thereof upon its axis, a latch element connected with one of said members, and complementary latch elements connected with the other of said members and adapted to engage said first mentioned latch element upon both sides thereof, one of said latch elements being retractile whereby to permit 105 the release of such engagement, said latch elements being adapted when engaged to prevent relative movement between said frame member and housing in either direction.

11. An outboard motor including a normally upright housing, propulsion mechanism supported therefrom and dirigible therewith, a tiller supported for oscillation co-axially with said housing, and means for releasably latching together said tiller and 110

housing against relative movement in either direction.

12. An outboard motor including a housing rotatably adjustable upon its axis, a 5 propulsion device supported from said housing and dirigible therewith, a tiller having a grip portion adjustable in an upright plane about a horizontal axis, latch mechanism operable to effect a positive two-way 10 connection between said tiller and said housing, and a latch releasing device extending from said latch mechanism along said tiller to the grip portion thereof.

13. In an outboard motor the combination 15 with a rotatably adjustable housing and a propulsion device supported therefrom, of a manually dirigible member mounted for oscillation co-axially with said housing, and a manually releasable lock associated with 20 said dirigible member and adapted in a plurality of positions of said housing to lock said member to said housing against relative movement in either direction.

14. In an outboard motor the combination 25 with a normally upright shaft housing providing a plurality of radially projecting lugs, of a manually rotatable casing adjustable co-axially with said housing, manually actuatable means within said casing for releasably engaging said lugs upon opposite sides, whereby when said means is operative said casing will be locked to said housing against relative movement in either direction.

15. In an outboard motor the combination 30 with a rotatably adjustable housing, a submersible propulsion mechanism and steering fins supported therefrom, of a casing manually rotatable co-axially with said housing, a plurality of radially projecting lugs within the casing, a set of opposed dogs pivotally mounted within said casing and normally spring pressed into the path of said lugs, and means for manually actuating one of 45 said dogs to releasing position.

16. In an outboard motor the combination 50 with a housing provided with lugs and rotatable upon its axis and a submersible propulsion device and steering fin supported from said housing and dirigible therewith, of a tiller mounted for oscillation co-axially with said housing, dogs pivotally connected with said tiller and oppositely disposed with reference to said lugs, means 55 normally pressing the extremities of said dogs into the path of said lugs, said dogs being adapted to oppose lug movement in opposite directions, and means associated with said tiller for manually releasing said 60 dogs.

17. In an outboard motor the combination 65 with a housing rotatable upon its axis and a submersible propulsion device and steering fin supported from said housing and dirigible therewith, of lugs projecting radially

from said housing, a tiller mounted for oscillation co-axially with said housing, dogs pivotally connected with said tiller and oppositely disposed with reference to said lugs, means normally pressing the extremities of said dogs into the path of said lugs, said dogs being adapted to oppose lug movement in opposite directions, and means associated with said tiller for manually releasing said dogs, one of said dogs being 75 provided with a cam surface and operable as a pawl by the lugs in the course of their rotation.

18. In an outboard motor, a releasable latching device comprising the combination 80 with a member rotatable for reversing purposes and rotatably adjustable for steering purposes, of a casing enclosing a portion of said member, lugs connected with the member within the casing, a dog pivoted within the casing and provided with a shoulder normally disposed in the path of said lugs, a spring pressed pawl pivoted within the casing and adapted to oppose relative movement between the casing and the lugs in a 90 direction opposite to that of the relative movement opposed by said dog, a member 95 slidable through said casing to engagement with a portion of said dog, a tiller connected with said casing, rotatable means associated with said tiller, and motion transmitting connections adapted to transmit the rotation of said last mentioned means into reciprocatory movement of said member 100 slidable in the casing, whereby said dog may be actuated to releasing position.

19. In an outboard motor the combination 105 with a housing oscillatory upon its axis for steering purposes and rotatable for reversing purposes, of a casing enclosing a portion of said member, latch mechanism adapted releasably to connect said casing with said member, a bearing sleeve projecting laterally from said casing, a tiller device journaled upon said sleeve for adjustment in 110 a vertical plane, a push rod reciprocable within said sleeve and connected with said latch mechanism for the control thereof, and a rotatable shaft associated with said tiller and provided with a lever operatively 115 associated with said reciprocable rod irrespective of the position of adjustment of said tiller.

20. In an outboard motor the combination 120 with a member rotatable upon its axis for reverse of said motor and oscillatory upon its axis for the steering thereof, of a manually dirigible casing, latch mechanism therein adapted to effect a releasable engagement between said casing and said member, a bearing sleeve projecting laterally from said casing, a tiller having an elbowed portion journaled upon said sleeve, a rod extending through said elbowed portion and said sleeve and adapted to confine the tiller to 125

- its place upon said sleeve, a reciprocable sleeve disposed within the first mentioned sleeve and concentric with said rod, a shaft within said tiller having its axis offset from 5 the axis of said rod, a lever mounted upon said shaft and provided with a forked extremity including a portion of said rod and operatively engaging said reciprocable sleeve, and a tiller grip connected with 10 said shaft, whereby the rotation of said tiller grip is adapted to effect the reciprocation of said sleeve and the release of said latching mechanism.
21. In an outboard motor the combination 15 with a steering and reversing member, a lug carried by said member, a casing adjustable co-axially with said member, a dog pivoted within said casing and provided with a portion movable into the path of 20 said lug, said dog being provided with a forked extremity, a bearing sleeve project-
- ing laterally from said casing, an elbowed tiller device journaled upon said sleeve, a rod extending through said casing and through said sleeve and the elbow of the 25 tiller, a reciprocable sleeve guided within the bearing sleeve and slideable upon said rod in engagement with the forked end of said dog, a spring guided upon said rod and seated at one end against the side of the 30 dog opposite to that engaged by said reciprocable sleeve, a shaft mounted within the tiller with its axis offset from the axis of said reciprocable sleeve, a lever carried by said shaft and provided with a forked 35 end including said rod and including said reciprocable sleeve, and manually operable means adjacent the end of said tiller for rotating said shaft, whereby the movement of said dog to releasing position may be 40 effected.

JAMES A. MOULD.
